(57) **CLAIM**

The ornamental design for an angled bifilter housing, as shown and described.

DESCRIPTION

FIG. 1 is a front perspective view of an angled bifilter housing;

FIG. 2 is a left side view thereof;

FIG. 3 is a front view thereof;

FIG. 4 is a right side view thereof;

FIG. 5 is a back view thereof;

FIG. 6 is a top view thereof;

FIG. 7 is a bottom view thereof; and,

FIG. 8 is an environmental view thereof showing filter installation with the filters shown in broken lines.

The broken lines illustrate the environment in which the article embodying the design is used and form no part of the claimed design.
